D. M. WALL,

BLADE PENDANT.

APPLICATION FILED AUG. 11, 1921.

1,417,872.

Patented May 30, 1922.

INVENTOR.

INVENTOR,
David M. Wall
BY Horatio E. Bellows
ATTORNEY

UNITED STATES PATENT OFFICE.

DAVID M. WALL, OF PROVIDENCE, RHODE ISLAND.

BLADE PENDANT.

1,417,872.

Specification of Letters Patent. Patented May 30, 1922.

Application filed August 11, 1921. Serial No. 491,631.

To all whom it may concern:

Be it known that I, DAVID M. WALL, a citizen of the United States, residing at Providence, in the county of Providence and State of Rhode Island, have invented certain new and useful Improvements in Blade Pendants, of which the following is a specification.

My invention relates as a new article of manufacture to a blade pendant.

The essential objects of my invention are to combine in an ornamental pendant for a chain or other article, a cutting or a razor blade; to disclose the blade in a position and condition for temporary use; and to attain these ends in a durable, inexpensive and sightly structure capable of facile manipulation.

To the above ends essentially my invention consists in such parts and in such combinations of parts as fall within the scope of the appended claims.

In the accompanying drawings which form a part of this specification

Figure 1 is a side elevation of a pendant embodying my invention.

Figures 2 and 3, sections of the same in open and closed positions respectively taken on line 2—2 of Figure 1,

Figures 4 and 5, sections on lines 4—4 and 5—5 respectively of Figure 2, and

Figures 6, 7, and 8 perspective views of several of the detailed parts.

Like reference characters indicate like parts throughout the views.

My device comprises a sheet metal box or housing 10 comprising front and rear walls 11 and 12, side walls 13, and a closed top 14 which in this case is a cap fast to the lateral walls by solder and provided upon its central portion with a perforated projection 15 in which is engaged a suspension ring 17. The bottom of the housing or casing is open as at 20, but closable by a cap or cover 21 provided with a marginal angular recess 23, adapted to receive a beveled catch projection 24 upon the wall 11, disengageable by inwardly pressing the wall area adjacent the projection.

Fast to the wall 12 by solder or otherwise is a longitudinally disposed member 25 shown in detail in Figure 6, comprising an attaching base 27 and lateral inclined diverging guide flanges 28. The base is provided at its upper end with a longitudinal

slot 29 whose lower end forms a stop shoulder 30.

Slidably mounted on the guides 28 is an oblong plate 32, shown in detail in Figure 7, provided with lateral inclined converging flanges 34 adapted to overlap and slidably engage the flanges 28. Upon the upper end of the plate 32 is a hook 36 adapted to slide in the slot 29 of the track member 25. Upon its lower end is a curved lug 37 fastened to the cover 21 by solder. In longitudinal alignment with each other along the center of the plate are studs 39, 40, and 41. The end studs 39 and 41 have preferably rounded ends, and the intermediate stud is preferably provided with a thread 43 to receive a knurled binding nut 44.

Resting on the slide plate 32 is an oblong blade 46 having opposite cutting edges 47 and provided centrally with a longitudinal series of holes 49, 50, and 51 adapted to admit loosely therethrough the studs 39, 40 and 41 respectively.

An oblong clamping plate 53, shown in detail in Figure 8, is provided preferably with inclined lateral edges 54, to afford some resiliency, and has a longitudinal series of perforations 56, 57, and 58 to loosely admit therethrough the studs 39, 40, and 41 respectively. This plate or its edges rest on the blade 46 and is pressed in contact therewith by the thumb nut 44. It will be noted that substitution of blades is afforded by removing the nut and the plate 53.

When desired the cover 21 may be unlatched as described and the blade carrying parts may be slid to exposed and operative position as shown in Figure 3. In which movement the slide plate is prevented from excessive outward travel by the contact of the hook 36 with the shoulder 30. Accidental return of the slide plate is prevented by virtue of an inclined spring arm 60 fast at one end 61 by a rivet 62 to the rear of the slide 32, and provided near its end with a shoulder 64 and terminating in a finger 65. When the parts are closed the arm 60 is compressed, but when opened the released shoulder 64 abuts against the end of the wall 12.

105

I claim:

1. In a blade pendant, a casing including an open end and a closed end, an attaching ring on the closed end, a detachable cap on the open end, a slide in the casing fast to

110

the cap, a blade on the slide, a clamping plate on the blade, and means for binding together and clamping the blade and the plate.

- 5 2. In a blade pendant, a casing provided with an open end, an attaching ring on the casing, a closure cap engaging the open end, a catch on the casing engaging the cap, a plate fast to the inner face of the casing, 10 guide flanges on the plate, a slide resting on the flanges and fast at one end to the cap, flanges on the slide slidably engaging the first flanges, a clamping stud on the slide, aligning studs on the slide beside the 15 first stud, a blade resting on the slide provided with holes to receive the studs, a plate on the blade provided with perforations to admit the studs, and a nut on the clamping stud engaging the last mentioned plate.
- 20 3. In a blade pendant, a casing provided with an open end, a projection on the casing

near the end, a detachable cap on the casing over the opening engaging the projection, a plate fast to the casing provided with a longitudinal slot, inclined lateral flanges on 25 the plate, a slide resting on the flanges and fast to the cap, inclined flanges on the slide overlapping the first flanges, a tongue on the slide registerable in the slot, and a blade detachably mounted on the slide. 30

4. In a blade pendant, a casing provided with an open end, a cap detachably mounted on the casing over the open end, internal guide flanges carried by the casing, a slide engaging the flanges and fast to the cap, a 35 resilient arm fast to the slide, a shoulder on the end of the arm, and a blade detachably mounted on the slide.

In testimony whereof I have affixed my signature.

DAVID M. WALL.
